SPIROMETER MEDICAL APPARATUS

Bernard N. Gray, East Pepperell, and John W. Burke,
Melrose, Mass., assignors to Life Support Equipment
Corp., Burlington, Mass.

Filed Feb. 26, 1971, Ser. No. 119,434

Term of patent 14 years

Int. Cl. D24—01

U.S. Cl. D83—1 F

FIG. 1

FIG. 2

FIG. 3

FIG. 4

FIG. 5

FIG. 6

FIG. 1 is a front elevational view of the spirometer medical apparatus embodying our new design;

FIG. 2 is a top plan view of the spirometer medical apparatus;

FIG. 3 is a side elevational view of the spirometer medical apparatus depicted in FIG. 1;

FIG. 4 is a rear elevational view of the spirometer medical apparatus of FIG. 1;

FIG. 5 is a bottom plan view of the spirometer medical apparatus embodying our new design; and

FIG. 6 is a front perspective view thereof.

We claim:

The ornamental design for a spirometer medical apparatus, substantially as shown.
